UNITED STATES PATENT OFFICE

152,963

DESIGN FOR AN ELECTRIC HEATER

Donald L. Hadley, Meriden, Conn., and Florence Santner Barron, Washington, D. C., assignors to Westinghouse Electric Corporation, a corporation of Pennsylvania

Application February 24, 1947, Serial No. 137,137

Term of patent 14 years

(Cl. D81—19)

To all whom it may concern:

Be it known that we, Donald L. Hadley and Florence Santner Barron, citizens of the United States, residing at Meriden, in the county of New Haven and State of Connecticut, and at Washington, in the District of Columbia, respectively, have invented a new, original and ornamental Design for an Electric Heater, of which the following is a specification, reference being had to the accompanying drawing, forming a part thereof, in which:

Figure 1 is a front elevational view of an electric heater embodying our new design;

Fig. 2 is a back elevational view thereof;

Fig. 3 is a top plan view thereof; and

Fig. 4 is an end elevational view thereof.

We claim:

The ornamental design for an electric heater, substantially as shown.

DONALD L. HADLEY.

FLORENCE SANTNER BARRON.
